Application November 15, 1944, Serial No. 563,566

7 Claims. (Cl. 60—35.6)

1

The present invention relates to apparatus for starting and controlling the operation of jet reaction or rocket motors producing a useful propulsive thrust by the recoil action of a high-velocity gas jet, particularly reaction motors actuated by the continuous combustion in a chamber of two or more liquid propellants fed under pressure to the motor from tanks.

In operating a reaction motor of the liquid propellant type, several preliminary operations are performed before the motor can be started, and it is the principal object of the present invention to provide improved control devices for carrying out such preliminary operations.

The apparatus includes liquid propellant tanks connected to the motor through pressure operated valves and to the firing chamber of the motor through magnetically operated valves. A single switch is provided which, when closed, initiates a chain of events to first connect the tanks to a source of nitrogen pressure from which the liquid in the tanks is subjected to a predetermined pressure. When this pressure is attained, a pressure switch is operated to cause purging of the firing chamber and operation of the magnetically operated valves to introduce a combustible mixture into such chamber, which is ignited by a spark plug. The pressure in this chamber produced by the combustion therein operates a pressure switch, when the pressure reaches a predetermined value, and brings about the opening of the pressure valves in the main propellant conduits, whereby the motor is placed in operation with the propellants being ignited by the heat of combustion in the firing chamber. The resulting increased pressure in the motor operates a further pressure switch to cut off the supply of propellant to the ignition chamber, and the motor continues to operate uninterruptedly.

It is a further object of the invention to provide control devices in the system whereby, upon failure of either current or operating pressure, the main propellant supply valves will automatically close and the motor will be automatically purged of any unburned fuel.

A more specific object of the invention is to provide an improved starting control device for a reaction motor wherein an initial flow of propellant fluid is fed to the motor and ignited, and in which the pressure resulting in the motor from said initial ignition causes increased flow of propellant fluid to the motor.

A still further object of the invention is to provide a multiple valve control between the fluid tank and the motor in which control pressure

2

causes closure of one valve and opening of a second, so that for operation pressure is required for one valve and removal of pressure is required for the other.

Another object of the invention is to provide a device for effecting a water and hydrocarbon mixture to the motor through a pressure closed valve, and in which failure of the valve to close will cause water to flush the motor.

A still further object is to provide a reaction motor of improved construction wherein more efficient intermingling of propellants is attained and more efficient heat exchange is obtained.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a diagram showing the interconnecting conduits and circuit connections employed in the apparatus of the invention.

Fig. 2 is a sectional view of the improved reaction motor.

Fig. 3 is a diagrammatic showing of a normally open, pressure operated valve used in the system.

Fig. 4 is a diagrammatic showing of a normally closed, pressure operated valve.

Fig. 5 is a diagrammatic showing of a safety head.

Fig. 6 is a diagrammatic showing of a pilot valve used in the system.

The complete coordinated system is diagrammatically illustrated in Fig. 1 and includes reaction motor M, liquid oxygen, gasoline and water reservoirs designated T1, T2 and T3 respectively. Intermediate the reservoirs and motor is a pair of like valves separately designated V1 and V2, and a further pair of like valves separately designated V3 and V4. Above each tank T1, T2 and T3 there is provided a valve V5, V6 or V7, whose construction is similar to that of valve V1 and V2. A further regulator valve R2 is also provided to regulate the application of nitrogen gas pressure from pressure spheres S1 to the several valves. Valves V1, V2, V5, V6 and V7 are gas operated valves in which gas pressure, when applied, will close a normally open valve. A bulletin entitled "General Controls," catalogue No. 51 (1941) published by the General Control Company of New York, illustrates a cross-sectional view of such valve on page 9 thereof. Figure 3

55 of the drawings shows a diagrammatic repre-

sentation of one such valve for example, valve V1. Valves V3 and V4 (see Figure 4) are normally closed valves and a section of such a valve is shown on page 20 of the catalogue referred to. Safety heads SH (see Figure 5) are of the well known type illustrated in a folder issued to the trade by Black, Sivalls and Bryson, Inc. of Kansas City, Mo., entitled "B. S. & B. Safety Head Pieces." Pilot regulator R1 (see Figure 6) is of the well known type illustrated in a folder issued by the Grove Regulator Company of Oakland, Calif., entitled "Grove Automatic Dome Loader." Valves SV3, SV5, SV6 and SV7 are well known magnetic valves illustrated on page 36 of catalogue 51 referred to. Switches PS1, PS4, etc. are well known valve-operated switches of the type manufactured by Cook Electric Company of Chicago, Ill.

Interconnecting the several devices identified is a network of conduits including a number of other hand, check, pressure relief and magnetically operated valves of well known types, whose detailed construction need therefore not be specifically illustrated.

A valve of the V1 type is represented in Fig. 3 wherein conduit 127, for example, enters into a chamber 136 which has connection through a port 137 with an exit conduit 138. Suspended above port 137 is a valve closure member 139 secured to resilient diaphragm 140 which normally holds the member 139 in the position shown. When gas pressure is applied through conduit 112 to chamber 141 the diaphragm is flexed to force member 139 into valve closing position. Upon release of the pressure, spring 142 causes reopening of the valve.

A valve of the V3 type is represented in Fig. 4 wherein conduit 60, for example, enters into a chamber 143 which has connection through a port 144 with an exit conduit 48. A valve member 145, urged by a spring 146, normally closes the port, and this member has a rod connection 147 with the center of a diaphragm 148. When gas pressure is applied through conduit 17 to chamber 149, the diaphragm is flexed to lift rod 147 and valve member 145 to open the port. Upon release of the pressure, spring 146 causes reclosure of the valve.

Fig. 5 shows a well known form of safety head in which a conduit such as 150 connects with a chamber 151 closed by a diaphragm 152 with a predetermined bursting limit, so that if the pressure in the chamber exceeds the limit, diaphragm 152 will burst and the pressure relieved to the atmosphere through opening 153.

Fig. 6 shows diagrammatically a well known form of pilot regulator R1 which supplies pressure to a conduit such as 155 from a conduit such as 154 which latter is under a pressure greater than the maximum delivery pressure desired. In operation, the manually operated handwheel 156, 60 rotatable in housing 157, increases the tension of a spring 158, against diaphragm 159, which through integral box 160 and rod 161 forces ball 162 into valve opening position to effect a connection from conduit 154, through port 163, chamber 164 to conduit 155. When this pressure, acting on the under side of diaphragm 159, produces a force equal to the adjusted spring tension, the diaphragm rises, and ball 162 under the action of its spring 165, closes the port 163. Reduction of the spring tension, is accompanied by rising of box 160 away from a ball 166, normally closing a port 167, so that the pressure in chamber 164 is relieved through opening 168, port 167 and opening 169 to the atmosphere, thus auto-

5 matically bleeding enough gas to maintain the adjusted pressure at the set point.

6 A control panel 10 has switches mounted thereon by means of which electric circuits are controlled to initiate and control the operation of the apparatus as will be set forth hereinafter. Before doing so, a brief description will be given of the structural arrangement of the motor shown in Figs. 1 and 2.

10 *The reaction motor.*—The motor M shown in Figs. 1 and 2 is of the self-cooled or regenerative type and consists of an inner combustion chamber 24, wherein combustion occurs, and an expansion nozzle 25 through which the burning gases are expelled, thereby producing a propulsive thrust. To prevent overheating of the combustion chamber 24 and nozzle 25 by the hot gases, an external cooling jacket and baffle 27 are provided. These are separated from chamber 24 and nozzle 25 by a narrow annular passage 28. One of the liquid propellants (gasoline and water) is fed to the annular space outside baffle 27 and flows through passage 28, thereby cooling nozzle 25 and chamber 24. The propellant is thereby heated and escapes into the interior of chamber 24 through ports 29, mixing with the other propellant (liquid oxygen) which is injected through ports 30 from manifold 31. Between baffle or filler block 27 and jacket 26 there is arranged a ring of spacer fins 27a which serve to break up the combustible entering through port 123. Along the length of passage 28 there are further rings of spacer fins 26a, inclined as shown, so that as the propellant travels through passage 28 it is broken up by fins 26a and given a spinner motion which serves to break up gas and liquid films and bubbles that may be present. Within oxygen ports 30 are located spiral springs 30a which serve to give a spin to the oxygen streams and make for better combustion and mixing of the propellants.

35 The spinner rings 26a and 27a, in addition to creating turbulence as the fuel passes through, serve to obtain an even distribution of the fuel over the outer surface of chamber 24. This is especially important since the intense heat within the chamber will cause burning at spots or areas where no heat exchange takes place. The angle of inclination of the slots in rings 26a and 27a and the width thereof is such that no longitudinal stream may form and the fuel will be evenly guided.

40 In this type of reaction motor illustrated, the temperatures attained in the combustion chamber are in the neighborhood of 3500° centigrade, and it is therefore extremely important that the propellant flowing through passage 28 be moved at a rapid rate and also that it be so evenly distributed over the outer surface of chamber 24 as to prevent burning out of the chamber wall. In the prior art of reaction devices that were utilized to drive turbine blades or the like, temperatures were necessarily considerably lower to avoid burning the turbine blades and therefore heat exchange problems such as encountered herein, where the motor is the prime mover, were not encountered.

45 The provision of baffles 26a, 27a or equivalent devices is necessary to obtain a uniform distribution of coolant, as without such devices the coolant would seek to flow in a restricted stream developing air pockets of uncooled wall space, which at the high temperatures noted would result in a hole being burned through the wall at that pocket. The spacing forming the passage 28 between wall 24, 25 and baffle 27 and jacket 26 is

made quite narrow, as this will assist in the distribution of the coolant and in its more rapid flow.

The ignition burner.—The ignition burner comprises a firing chamber 32 suitably secured to the motor proper and is provided with an oxygen intake port 33 and a gasoline intake port 34, which ports are constructed to effect a readily combustible mixture which is ignited by the spark plug 35 and passes out through orifice 36 into the main combustion chamber 24, producing an intense flame which ignites the combustible mixture in chamber 24. As will be explained in detail hereinafter, a charge of combustible mixture is first fed to the firing chamber 32 and, when this has become ignited, the pressure within the chamber will cause operation of valves through which propellants may thereafter be fed to the main combustion chamber 24. The inner end of spark plug 35 is surrounded by a passage 37 having a port 38 through which a small stream of nitrogen gas is continuously directed around spark plug 35 to dry and cool the latter. This gas stream is kept small enough to avoid interference with the ignition of the fuel mixture in the firing chamber.

Valve system.—The propellants are contained in the three pressure tanks T1 (liquid oxygen), T2 (gasoline) and T3 (water). Safety heads SH containing diaphragms set to burst before excessive tank pressure develops are provided on these tanks. The tanks are filled through filling valves H1. The usual tank pressure is 300 lb./sq. in. and is provided by feeding nitrogen gas into the tanks from regulator valve R2, which in turn is fed from a set of three high-pressure spherical nitrogen tanks S1. The nitrogen spheres are charged through valve H1 from a battery of commercial nitrogen cylinders or a pump. A safety head SH with bursting diaphragm protects the spheres against excessive pressure. Shut-off valves H2, H11, H12 are provided to isolate regulator valve R2 from the tanks when repairing or adjusting it. The regulator R2 is controlled by gas pressure supplied through conduit 97 by a pilot regulator R1, as explained later.

The propellants are fed to the reaction motor M through valves V1, V2, V3 and V4. The main valves V1 and V2 control the flow of liquid oxygen and of mixed gasoline and water respectively. They are mounted close to the motor to provide a rapid fuel shut-off and are normally open when the control gas pressure is shut off. To provide against failure to shut off the propellants in case of damage to valves V1 or V2 or malfunction of them, a second set of emergency or safety valves are provided, oxygen valve V3 and gasoline valve V4, which are normally closed when control gas pressure is shut off. These are mounted near the propellant tanks some distance from the motor, and are operated by a separate set of controls as described later. No safety valve is provided for the water, so that motor M is automatically flushed out with water if valve V2 fails to close.

Another set of diaphragm valves V5, V6 and V7 are connected to the tops of the propellant tanks to vent off the gas pressure in these tanks after completing a run. These valves are normally open when control gas pressure is shut off. The oxygen tank vent V5 exhausts directly into the air at 125. The water tank vent V7 is connected to the oxygen valve V1 by way of conduit 127, and the gasoline tank vent V6 is connected to the gasoline valve V2 by way of conduit 126. This ensures that any propellant remaining in the valves,

fuel lines, and motor after a run will be thoroughly purged out by the vented nitrogen gas.

At the beginning of a run, gasoline is supplied to the ignitor by way of conduit 119, which includes a solenoid valve SV2 and metering orifice 101 (which also includes a filter screen and check valve 132). Oxygen gas is supplied to the intake port 33 of the ignitor through the evaporator coil E (heated by the surrounding air) and the solenoid valve SV1.

The control pressure for controlling regulator valve R2 is provided by the pilot regulator valve R1, which feeds nitrogen gas at 350 lb./sq. in. To ensure that nitrogen pressure will still be available to operate the controls in case of exhaustion of the pressure in tanks S1, a small high-pressure sphere S4 is provided ahead of regulator R1, isolated from the main nitrogen spheres by a check valve 133. The nitrogen feed from pilot regulator R1 is turned on and off by the solenoid valve SV4. From SV4 the nitrogen control pressure system branches off in several directions. A three-way solenoid valve SV3 leads to regulator R2. Valve SV3 is normally vented in the off position, but feeds nitrogen to regulator R2 when its solenoid is energized. This pressure is applied to the right side of the diaphragm R2a in regulator R2, thereby causing the valve R2b in R2 to open and feed nitrogen to the tanks T1, T2, T3 until the tank pressure reaches 300 lb./sq. in., when regulator R2 will shut off. Diaphragm R2a has a connection with valve R2b, as shown so that valve R2b follows the movement of the center of diaphragm R2a. Thus pressure applied to the right side of R2a will cause valve R2b to shift to the left and uncover the end of conduit 98 to allow nitrogen to flow into the chamber of the valve and out through conduits 81 and 82. (The difference of 50 lb./sq. in. in outlet pressure of R1 and R2 is owing to the force required to push the valve R2b in R2 open against the nitrogen pressure.)

Control for working the main propellant valves V1 and V2 is supplied through the three-way solenoid valve SV5 (a "normally open" valve). When current is off, fluid pressure is supplied to valves V1, V2 closing them. When the solenoid of valve SV5 is energized, the pressure is vented, causing valves V1, V2 to open. The vent valves V5, V6, V7 are actuated by another three-way solenoid valve SV7 of the "normally-closed" type. When SV7 is "off," the control pressure is vented from valves V5, V6, V7, causing them to open, while when the solenoid of valve SV7 is energized, V5, V6, V7 are closed. It will be noted that the safety valves V3 and V4 are connected to the same control pressure lines as the valves V5, V6, V7, so that when the latter are open the safety valves are shut, and vice versa.

Another three-way solenoid valve SV6 is provided for purging the spark plug 35 with nitrogen gas after each run. The valve SV6 is connected to a small tank T4. When valve V6 is "off," T4 is connected to regulator R1 by way of valve SV4, and charges up to 350 lb./sq. in. When the solenoid of valve SV6 is energized, tank T4 is disconnected from regulator R1 and vented off through a check valve 130 horizontally to the right of valve SV6, and the interior of spark plug 35, thereby purging out any gasoline or water lodged in the plug and ignitor, leaving them clean and dry. A small orifice 102 bypasses valve SV6 and causes a small stream of nitrogen gas to circulate continuously through plug 35 to dry and cool the latter. This gas stream is kept small

enough to avoid interference with the ignition of the fuel mixture in the burner.

Two pressure switches PS2 and PS3 (set to close at 125 lb. and 50 lb./sq. in. respectively) and a pressure gage G3 are attached to the purge line leading to plug 35 and the burner. The switches control the action of the various solenoid valves, as described later. The gage G3 indicates the pressure in the ignition burner. Since this pressure is the same as that in the main motor M when the latter is firing, gage G3 also serves to indicate the main motor pressure, and thus the propulsive thrust, since the latter is nearly proportional to the combustion chamber pressure.

Another pressure switch PS1 (set to close at 250 lb./sq. in.) is connected to tank T1 through hand valve H6, while a fourth pressure switch PS4 (set to open at 15 lb./sq. in.) is connected to tank T4.

For convenience in setting and adjusting the pressure switches, a set of hand shut-off valves H5, H6, H7 are provided. To set the pressure switches, regulator R1 is set to zero pressure, valves H3, H4, H6 and H13 are all closed, valves SV4, H5, H7 are opened, and pressure is fed to the purge line and the switches by slowly opening regulator R1 manually. The pressures at which the various switches close (as indicated by a test light or voltmeter connected to them) are noted on pressure gage G2 connected to the output of regulator R1, and any necessary adjustments of the switches are then made. To lower the pressure, H7 is closed and H13 slowly opened so that the pressure is relieved through the spark plug 35 and the combustion chamber. (See Fig. 2.)

To check main regulator R2, valves H4, H5, H7, H11 and H12 are closed and valves H3 and H2 left open. Regulator R1 is then adjusted until the output pressure of regulator R2 as indicated by gage G4 reaches the proper amount. The corresponding pressure on gage G2 is then noted, and regulator R1 is thereafter always set to give this operating pressure. To release the pressure in R2, valve H3 is closed and H4 is opened, allowing the pressure to leak off through the vent in valve SV3.

In normal operation, valves H2, H4, H6, H11, H12 and H13 are left open, while valves H1, H3, H5, and H7 are closed, together with filling valves H8.

Operation.—On the control panel 10 (Fig. 1) is a key switch SW1 which, when closed (after safety switch SW2 has been closed), will supply current from battery B to wire 103 and to an indicator lamp 104. There is also a three position switch represented by a pair of contact arms 105 shown in normal "off" position, which are movable concurrently to a "start" or horizontal position and to an upper or "run" position. These positions are designated 1, 2 and 3 in the drawings.

When switch arms 105 are moved to their 2 or "start" position, the solenoids of valves SV3, SV4 and SV1 will become energized through a circuit traceable from battery B, switches SW2, SW1, left hand arm 105, wire 106 and in parallel through the solenoids of the three valves to ground. Operation of valve SV4 permits nitrogen to flow from pilot regulator R1 to conduits 107, 108 and 109 and operation of valve SV3 connects conduit 108 to conduit 97, so that regulator valve R2 will have pressure applied thereto to open said valve, whereupon pressure from the spheres S1 is exerted through conduit 98, and conduits 81 and 82 to the tanks T1, T2 and T3.

When the tank pressure reaches 250 lb./sq. in., pressure switch PS1 is operated through conduit 110 to close contacts PS1a which thereupon complete a circuit from wire 103, contacts PS1a, and lamp 111 to ground to indicate that tank pressure is on. Operation of valve SV1 closes the vent therethrough and connects conduit 109 to conduit 112, so that pressure from pilot regulator R1 is exerted through conduits 109 and 112 to valves

10 V5, V6 and V7 to close them. This occurs while pressure is building up in the tanks, so that the vent valves are closed when the operating pressure of 250 lb./sq. in. is reached. Pressure from conduit 112 also branches through conduits 117 to valves V3 and V4 to open these valves. Opening of valve V3 connects valve V1 with tank T1 and opening of valve V4 connects valve V2 with tank T2 through conduit 113, and a box or chamber 113a into which water is also directed from tank T3 through conduit 114. Both the gasoline and water are fed under pressure (250 lb.) into chamber 113a wherein they commingle and pass through conduit 123 to the motor when valve 12 opens. The valves V1 and V2 are held closed at this time through nitrogen pressure from conduit 109, through normally connecting valve SV5 and conduits 122 and 51 and will open as soon as this pressure is cut off by operating valve SV6 to vent conduit 122.

30 Pressure in conduit 109 is applied through normally connecting valve SV6 to a small tank T4 and, as the pressure builds up in this tank, pressure switch PS4 operates to open its contacts PS4a. With the solenoid of valve SV6 deenergized as at present, conduit 109 is connected only to tank T4 and is disconnected from a conduit 116. The positions of the valves at this time may be termed their start or normal positions, i. e., at the start position valves V1 and V2 are closed.

40 Switch arms 105 are now moved to their 3 or "run" position where a circuit is now completed from battery B, switches SW2, SW1, wire 103, left arm 105 and wire 106 to maintain the solenoids of valves SV3, SV4 and SV1 energized. A further circuit is traceable from battery B, switches SW2, SW1, wire 103, contacts PS1a, right arm 105, wire 115, solenoid of valve SV6 to ground. Operation of valve SV6 disconnects tank T4 from conduit 109 (through which it has been charged) and connects it to conduit 118 and thence through the chamber 37 (Fig. 2) surrounding spark plug 35 to blow off and clear out any moisture or dirt in these parts. When the pressure in tank T4 has fallen to 15 lb./sq. in. or less (which occurs in a few seconds), the contacts PS4a of pressure switch PS4 reclose and through them a circuit branches from wire 115, through contacts PS4a, wire 117, contacts Ya of a relay coil Y, wire 118, which branches to solenoids of valves SV1 and SV2 and thence to ground. A branch wire 119 extends to primary winding of a spark coil SC whose secondary winding is connected to spark plug 35.

55 Operation of valve SV2 permits gasoline to flow through conduit 119 to the firing chamber 32 and operation of valve SV1 permits oxygen to flow from coil E to the chamber. Ignition thereupon takes place and a pressure of about 70 lb./sq. in. is developed in the firing chamber, which is transmitted through conduit 120 to switch PS3 to cause the related contacts PS3a to close. Closure of these contacts completes a circuit from wire 115, contacts PS4a, wire 117, contacts PS3a, and wire 121 to solenoid of valve SV5, closing this normally open valve to dis-

connect conduit 109 from conduit 122 and 51 and valves V1 and V2 to allow opening of these main propellant valves and permit a greater flow to motor M, through conduits 50 and 123.

As soon as the motor M develops a pressure of 125 lb./sq. in. or more (which occurs almost instantly), pressure switch PS2 is operated and closes its contacts PS2 to complete a circuit traceable from current line 115, contacts PS4a (reclosed), contacts PS2a, wire 124 to relay Y and ground. The relay opens its contacts Ya and closes its contacts Yb and Yc. Opening of contacts Yc deenergizes the solenoids of valves SV1 and SV2, shutting off fuel supply to the ignitor and current to the spark coil SC. Closure of contacts Yc sets up a holding circuit for the relay traceable from current wire 106, contacts Yc, and relay Y to ground, which will now maintain the relay energized until switch arms 105 are moved out of the 3 positions. The relay contacts Yb are wired in parallel with contacts PS3a and with the former now held closed the circuit through solenoids of valves SV5 is maintained energized to keep valves V1 and V2 open.

Motor M is now receiving a constant flow of oxygen through conduit 50, and a constant flow of a mixture of gasoline and water through conduit 123, and this will continue until the supply is exhausted or until switch arms 105 are shifted from their "run" positions.

If arms 105 are shifted to their 2 or start positions, the solenoids of valves SV3, SV4 and SV7 will be deenergized and immediately reenergized to keep pressure in tanks T1, T2 and T3. Switch PS1 will keep its contacts PS1a closed and lamp 111 will remain illuminated. With current interrupted to wire 115, solenoid of valve SV6 will become deenergized and pressure will build up again in tank T4, operating valve PS4 to open contacts PS4a and deenergize the solenoid of valve SV5. This results in connecting conduit 122 to pressure conduit 109, so that valves V1 and V2 are operated to cut off the fuel supply. Relay Y also becomes deenergized upon opening of its holding circuit, through the left switch arm 105. The apparatus is now in the condition as described, just prior to moving the switch from its start to run position.

To resume operation, the arms 105 are shifted back to run position and the sequence of events described will be repeated, beginning with tank T4 first blowing off to clear the ignition chamber.

It is to be particularly noted that, when switch 105 is moved from its run to start positions, all circuits are momentarily broken, including the circuit to the solenoid SV7 which thus causes momentary venting of conduit 112, so that valves V5, V6 and V7 open allowing pressure in tank T2 to vent through conduit 126 and tank T3 to vent through conduit 127 and 52 to thus purge the motor M of any unburned fuel before the circuit to solenoid SV7 is reestablished and insures that upon return to "run" position the motor will be free of combustible charge.

With arms 105 moved to "off" position (or by opening either switch SW1 or SW2), current is interrupted to all the solenoid valves. Valve SV1 is vented to atmosphere so that valves V5, V6 and V7 are vented through conduit 112, allowing these valves to open under pressure of the nitrogen in the tanks. Pressure in tank T1 will be vented through conduit 125 to atmosphere. Pressure in tank T2 will be vented through conduit 126, through valve V2, conduit 123 and

motor M, and pressure in tank T3 will be vented through conduits 127, 52, valve V1, conduit 50 and motor M, thus purging the motor of any unburned fuel.

It is to be noted that any current failure will shut off the motor in the same manner as though the switch were thrown to its "off" position, and it is to be further noted that failure of the nitrogen control pressure will also stop the motor, since if there is no pressure in conduit 112, valves V3 and V4 close to cut off the supply of propellants to valves V1 and V2. Any stoppage of the motor will also cause venting of the tanks T2 and T3 through the motor, so that the latter is purged and returned to a safe "off" condition.

In the foregoing it was stated that the switch is moved from its "off" to its "start" and then to its "run" position. It may also be moved directly from "off" to "run," in which case the same sequence of events occurs, namely, valves SV3, SV4, and SV7 operate concurrently and the tanks T1, T2, T3 become charged. Tank pressure will operate switch PS1 and the operation will follow as explained. The switch PS1, through its contacts PS1a prevents any operation unless sufficient pressure is first built up in tank T1.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a starting system for a reaction motor, a combustion chamber having an ignition device, in combination with a reservoir containing a liquid fuel, a conduit between said chamber and reservoir, a normally closed valve in said conduit, a source of gas pressure, means for connecting said reservoir to said pressure source to create pressure in the reservoir, means responsive to the pressure in said reservoir when it reaches a predetermined value for causing gas from said pressure source to purge said ignition device, and means effective upon completion of said purging for automatically opening said valve and for operating the ignition device, whereby fuel under pressure is fed to the chamber and ignited.
2. In a starting system for a reaction motor, a combustion chamber, a reservoir containing a liquid fuel, a conduit between said chamber and reservoir, a normally closed valve in said conduit, a pressure source, means for connecting said reservoir to said pressure source to create pressure in said reservoir, means responsive to the pressure in said reservoir when it reaches a predetermined value for causing opening of the valve in said conduit, whereby fuel under a predetermined pressure will pass to the chamber and further means responsive to the pressure in the chamber when it reaches a higher predetermined value for effecting reclosure of the valve.
3. In a starting system for a reaction motor, a combustion chamber having an ignition device, in combination with a reservoir containing a liquid fuel, a conduit between said chamber and reservoir, a normally closed valve in said conduit, a source of gas pressure, means for connecting

said reservoir to said pressure source to create pressure in the reservoir, an auxiliary tank containing a charge of gas under pressure, means responsive to the pressure in said reservoir, when it reaches a predetermined value for causing the charge of gas in said tank to exhaust through said ignition device to purge the same, and means responsive to the exhaustion of said charge for causing opening of said valve and for operating said ignition device, whereby fuel under pressure is fed to the chamber and ignited.

4. The invention set forth in claim 3 in which the valve is electrically operated, and the means responsive to the exhaustion of the charge in said auxiliary tank comprises a pressure switch connected to the tank and an electric circuit is provided and closed by said switch when the pressure in the tank drops to a predetermined value, to operate said valve.

5. In a starting system for a reaction motor, a combustion chamber having an ignition device, in combination with a reservoir containing a liquid fuel, a conduit between said chamber and reservoir, a normally closed valve in said conduit, a source of gas pressure, means for connecting said reservoir to said pressure source to create pressure in the reservoir, an auxiliary tank normally connected to said pressure source to thereby receive a charge of gas, means responsive to the pressure in said reservoir when it reaches a predetermined value for disconnecting the tank from said source and for causing the charge of gas in said tank to exhaust through said ignition device to purge the same, and means responsive to the exhaustion of said charge for causing opening of said valve and for operating said ignition device, whereby fuel under pressure is fed to the chamber and ignited.

6. In a system of the class described, a combustion chamber, a reservoir containing a liquid fuel, a main conduit and an auxiliary conduit between said reservoir and said combustion chamber, means for causing fuel to flow from the reservoir to the chamber through the auxiliary conduit, an ignition device in said combustion chamber operative to ignite the fuel fed thereto, means responsive to the pressure created in said chamber means controlled thereby when said

pressure reaches a predetermined value for causing fuel to flow from the reservoir to the chamber through the main conduit and further pressure responsive means effective when the pressure in the chamber reaches a higher predetermined value for shutting off the flow of fuel through the auxiliary conduit.

7. In a system of the class described, a combustion chamber, a reservoir containing a fuel, a main conduit and an auxiliary conduit between said reservoir and said combustion chamber, means for causing fuel to flow from the reservoir to the chamber through the auxiliary conduit, an ignition device in said combustion chamber operative to ignite the fuel fed thereto, means responsive to the pressure created in said chamber, means controlled thereby when said pressure reaches a predetermined value for causing fuel to flow from the reservoir to the chamber through the main conduit and further pressure responsive means effective when the pressure in the chamber reaches a higher predetermined value for rendering the ignition device ineffective.
